WIDE DESEAMING PROCESS AND NOZZLE

Arthur P. Scheller, Union, N. J., assignor to The
Linde Air Products Company, a corporation of
Ohio

Application June 7, 1946, Serial No. 674,943

4 Claims. (Cl. 148—9)

1

This invention relates to the thermochemical skin-scarfing of ferrous metal bodies by the oxy-fuel gas process, and more particularly to an improved wide deseaming process and blowpipe nozzle.

The main objects of the invention are to provide a deseaming nozzle for use with a standard blowpipe to produce substantially wider cuts; and an improved oxy-fuel gas ferrous metal skin-scarfing process.

As pointed out in Walker et al. Patent No. 2,266,834, dated December 23, 1941, when metal containing surface fissures or other surface defects is rolled, the defects are not eliminated and they are sometimes rolled into the body of the metal in the form of concealed unbonded seams or cracks. Also, when the surface of metal having steep projections thereon or grooves therein with steep sides is rolled out, the sides of these irregular surfaces fold over and include oxides within the folds and cause concealed cracks in the body of the metal in the same way.

In order to eliminate the defects and the formation of seams within the body of the metal it is necessary to remove the defective metal portions so that only sound bonded metal remains and so that the slopes of the depression and elevations that may be left on the surface of the billet will be so gradual that these slopes will not be folded over and rolled into the body of the metal when it is rolled.

Much time and labor are saved by removing the defective surface portions of the steel or iron thermochemically with the use of an oxidizing stream of gas. The desired contour of the groove cut by the oxidizing gas is obtained with a deseaming blowpipe nozzle constructed to permit the passage of a suitable volume of gas at a relatively low orifice velocity, such as, for example, about 585 feet per second. The contour of the cut is controlled by the shape of the orifice and the velocity of the oxidizing stream issuing therefrom. Velocities of the gas stream commonly used for oxygen cutting or severing of metals are equal to or higher than the velocity that is produced by gas flowing through a passage of uniform cross-sectional area. Therefore, the relatively low orifice velocity desired for removing surface metal is one which is below that commonly used for cutting kerfs.

Deseaming nozzles similar to the blowpipe nozzle shown in Figs. 1-3 of the Walker et al. patent are in widespread use in steel mills for hand deseaming steel slabs, blooms, billets and the like, in conjunction with deseaming blowpipes of the

2

type disclosed in Jacobson et al. Patent No. 2,284,574, dated May 26, 1942, involving the use of a starting rod.

Such blowpipe is provided with a mechanism for feeding metal wire or rod into the flame adjacent the end of the nozzle. A control lever pivotally mounted on the blowpipe adjacent the rear part of the handle is operatively associated with both the rod feeding mechanism and the means for controlling the supply of cutting oxygen. With the preheating flames lighted, the control lever may be swung through a part of its stroke to feed a short length of starting rod into the preheating flames.

15 During such first part of the stroke only the rod feed mechanism is actuated and the cutting oxygen valve remains closed. The lever is held in this position until the rod is heated at least to its ignition temperature, whereupon the lever is swung further to open the cutting oxygen valve. During this latter part of the stroke of the lever no additional feeding of the rod is caused by the rod feeding mechanism. Practically simultaneously with the opening of the cutting oxygen valve the blowpipe is moved or swung in the direction of the discharge cutting oxygen stream to deseam a ferrous metal body in a manner well known to those skilled in the art.

20

25 Prior to the invention deseaming cuts up to $1\frac{1}{4}$ inches wide having fairly uniform depths have been made. However, there exists a demand for wider cuts in a single pass, so that the number of passes can be reduced and the entire edge of a slab, for example, can be skin-scarfed by a single nozzle.

30 This is accomplished according to the present invention by providing a nozzle having the same seat construction and overall length as the standard deseaming nozzle, so as to make the apparatus as light in weight as possible and also capable of use with blowpipes already in use. However, the exit or outlet portion of the cutting oxygen passage in the nozzle is swaged to about double the diameter of the inlet portion.

35

40 To deflect the cutting oxygen uniformly against the wall of the outlet portion and fill such portion, thereby ensuring a uniform face velocity of the cutting oxygen with a minimum of turbulence, a 45 divergently drilled baffle is inserted in such outlet portion from the face end of the nozzle, and held in place at the inner end of such portion.

50 With the improved nozzle deseaming cuts substantially wider than those obtainable prior to the invention are possible. In fact, cuts more

than twice as wide have been made with excellent efficiency.

Referring to the drawing:

Fig. 1 is a longitudinal view in cross section of a deseaming blowpipe nozzle exemplifying the invention.

Figs. 2 and 3 are front and rear views, respectively, of such nozzle.

The blank from which nozzle N is formed comprises an elongated body 10 of heat conductive metal, such as copper, provided with a relatively large central passage 11 which extends axially throughout the length of the nozzle, for conveying cutting oxygen therethrough. The rear end of the tubular body 10 is provided with a seat 12 surrounding the entrance end of the passage 11. The seat 12 is adapted to form a hermetical seal with a complementary seat in a socket in the blowpipe head to which the nozzle is adapted to be connected. Oxygen gas is adapted to flow from the blowpipe head into the passage 11 from which it discharges onto the workpiece being treated.

A series of preheat or combustible gas passages 13 are arranged in generally parallel relation about the central passage 11. The rear ends or inlets of these passages terminate in an annular groove 14 which is spaced forwardly of the inlet end of passage 11. The groove 14 forms a gas-distributing chamber with a portion of the blowpipe head. A seat 16 surrounds the preheat passages 13 and forms a hermetical seal with a complementary seat in the socket of the blowpipe head. A combustible gas, such as a mixture of oxygen and acetylene, is fed to said gas-distributing chamber, thence through the preheat passages 13, and finally the gas mixture discharges from the outlets of said passages in the front end face F of the nozzle N, to provide an annular row of preheating flames.

An annular collar 17 is provided close to and forwardly of the seat 16, and is of such outer diameter that it cooperates with an integral shoulder 18 located at the extreme rear end of the nozzle N to provide an abutment for a hollow coupling nut 19.

A protective collar C is secured to the forward end of the nozzle N by an annular fillet weld 31, as disclosed and claimed in Egger et al. Patent No. 2,294,392, dated September 1, 1942. The hollow coupling nut 19 has screw threads 20 adapted to cooperate with complementary threads in the socket of the blowpipe head to which the nozzle is to be secured. The nut is rotatable and slideable axially relatively to and upon the outside surface of the nozzle N when coupling the nozzle to the blowpipe head, thus permitting any circumferential portion of the collar C to be located in work-contacting position and thereby affording a longer life for the nozzle, since the wear-resistant collar may then be adjusted so that it wears off evenly throughout its circumference.

While coupling the nozzle to a blowpipe head, an end of the nut bears against the collar 17. Furthermore, the abutments provided by flared portion 22' and collar 17, being of greater outside diameters than the inside diameter of the nut, prevent removal of the nut 19 from the nozzle, but permit sliding and rotation of the nut relatively to the nozzle.

The axially extending passage 11 of the elongated nozzle N is composed of an inlet portion 21 of constant diameter, a central flared portion 22 of frusto-conical shape, and an outlet portion 23 of constant diameter; the diameter of

the outlet portion 23 being about twice that of the inlet portion 21. A baffle 24 is fitted in the passage 11 at the juncture of the frusto-conical portion 22 and outlet portion 23. The baffle 24 is provided with a central axially extending orifice 25, and an annularly arranged series of orifices 26 the axes of which diverge downstream with respect to the longitudinal axis of the nozzle N.

The frusto-conical portion 22 controls the expansion of the confined stream of cutting oxygen as it leaves the inlet portion 21, to about four times the cross-section thereof, the expanded stream being broken up immediately after such expansion into a plurality of jets by the orifices 25, 26. The cutting oxygen jets, however, are recombined in the outlet portion 23 of the nozzle into a composite oxygen stream of uniform cross-sectional area. The composite stream of cutting oxygen is discharged from the outlet portion 23 into the atmosphere, and thereupon applied at an acute angle against the surface to be deseamed. Such surface is heated by the oxy-fuel gas flames discharged by the preheating gas passages 13, and thermochemical skin-scarfing is accomplished by advancing the composite stream of oxygen with respect to the heated surface, in the manner well known to those skilled in the art.

The nozzle and process of the invention have proved to be very effective for making exceptionally wide deseaming cuts which are more than twice as wide as the deseaming cuts possible according to the prior art. This is accomplished mainly because a relatively large flow of cutting oxygen is discharged from the nozzle N with a minimum of turbulence and at a substantially uniform face velocity. This is due to the fact that the major turbulence-producing pressure-shock of the oxygen stream directly upstream of the baffle 24, due to rapid expansion of the gas in the conical portion 22, is prevented by the baffle 24, while the minor turbulence-producing pressure-shocks, due to expansion of the smaller jets in the outlet portion 23, are neutralized by one another in such outlet portion as the jets recombine to form the composite oxygen stream which is discharged to the atmosphere from the portion 23.

What is claimed is:

1. An elongated nozzle having an axially extending fluid passage comprising an inlet portion of constant diameter, a central portion of frusto-conical shape, and an outlet portion of constant diameter, the diameter of the outlet portion being about twice that of the inlet portion, and a baffle in such passage at the juncture of the frusto-conical and outlet portions, said baffle having a central axially extending orifice and an annularly arranged series of orifices the axes of which diverge downstream with respect to the longitudinal axis of the nozzle deflecting outer portions of the fluid stream outwardly against the wall of the outlet portion to reduce turbulence and produce a discharged stream of substantially uniform face velocity.

2. A wide deseaming blowpipe nozzle having an elongated cutting oxygen passage provided with an inlet portion, a flared central portion, and an outlet portion, said inlet and outlet portions being about equal in length, the cross-sectional area of each substantially constant throughout the length thereof, and the cross-sectional area of the outlet portion being about four times that of the inlet portion; and means located in such

passage, at the juncture of said outlet portion and the flared central portion, consisting of a baffle having a central axially extending orifice and an annularly arranged series of orifices the axes of which diverge downstream with respect to the longitudinal axis of the nozzle for directing portions of the cutting oxygen stream outwardly against the wall of the outlet portion to reduce turbulence and produce a discharged stream of substantially uniform face velocity.

3. Process of wide deseaming which comprises heating the surface of a ferrous metal body to the ignition temperature with oxygen, expanding a confined stream of cutting oxygen to about four times the cross-sectional area thereof, breaking up the stream immediately after such expansion into a plurality of jets one of which jets is axially in line with such stream and the remainder of which jets are arranged annularly about such axial jet and are divergent with respect thereto, recombining such jets into a composite stream of uniform cross-sectional area equal in size and shape to that following the first expansion, discharging such composite stream into the atmosphere with a minimum of turbulence and at a substantially uniform face velocity, applying the discharged stream at an acute angle against the heated surface of such ferrous metal body, and thermochemically skin-scarfing the body by advancing the composite stream of 30 oxygen with respect to the surface thereof.

4. In the art of deseaming ferrous metal

- bodies by applying a stream of oxygen at an acute angle against the surface to be deseamed while heating the adjacent metal, the method of increasing the width of the cut which comprises expanding the cutting oxygen stream while it is still confined, separating and deflecting portions of the expanded stream outwardly immediately after expansion, and confining the resulting composite stream to an unobstructed path of uniform cross-sectional area prior to discharge into the atmosphere, which area is equal to that of such expanded stream, to provide a cutting oxygen stream of substantially uniform face velocity with a minimum of turbulence.
